(57) **CLAIM**

The ornamental design for a sound machine for sleep therapy, as shown and described.

DESCRIPTION

FIG. 1 is a front perspective view of a sound machine for sleep therapy according to an embodiment of the invention shown;

FIG. 2 is a rear perspective view of the sound machine of FIG. 1;

FIG. 3 is a front perspective view of the sound machine of FIG. 1;

FIG. 4 is a rear perspective view of the sound machine of FIG. 1;

FIG. 5 is a right side elevation view of the sound machine of FIG. 1;

FIG. 6 is a left side elevation view of the sound machine of FIG. 1;

FIG. 7 is a top plan view of the sound machine of FIG. 1;

FIG. 8 is a bottom plan view of the sound machine of FIG. 1;

FIG. 9 is a front elevation view of the sound machine of FIG. 1; and,

FIG. 10 is a rear elevation view of the sound machine of FIG. 1.

The broken dashed lines (---) showing in FIGS. 1-10 are included for the purpose of illustrating portions of the sound machine for sleep therapy that form no part of the claimed design.
